UNITED STATES PATENT OFFICE.

EMIL E. NOVOTNY, OF RIVERSIDE, ILLINOIS, ASSIGNOR TO J. STOGDELL STOKES, OF MOORESTOWN, NEW JERSEY.

RUBBER-FACED PRINTING-PLATE.

1,377,505.

Specification of Letters Patent. Patented May 10, 1921.

Application filed December 1, 1916. Serial No. 134,326.

To all whom it may concern:

Be it known that I, EMIL E. NOVOTNY, a citizen of the United States, and resident of Riverside, in the county of Cook and State of Illinois, have invented certain new and useful Improvements in Rubber-Faced Printing-Plates, of which the following is a specification.

My invention relates to a printing plate 10 wherein the printing face or impression-producing portion is composed of a frictional, resilient material such as rubber, backed with a body or layer of suitable material, preferably though not necessarily in 15 the nature of a plastic or cementitious product of which "bakelite" or "condensite" are examples.

One of the objects of the present invention is the provision of a printing plate of 20 this character which will transfer the ink more readily and satisfactorily than the ordinary electrotype, stereotype or etchings, especially under the conditions where a rough or thin paper is to receive a relatively fine impression.

Another object of my invention is the provision of a plate wherein the necessity of employing expensive or special make-ready is obviated, for by reason of the fact that 30 the face or printing portion of my plate possesses inherently a certain or predetermined degree of resiliency it will naturally, under the adjusted pressure of the press mechanism compensate for such variations 35 as are usually encountered in printing and which are provided for by make-ready.

Furthermore, it is my purpose to provide 40 a printing plate wherein results similar to letter, offset, litho, or intaglio press printing, or combinations of them, may be attained with the use of the ordinary letter printing press and with less labor on the part of the pressman preparatory to the actual printing.

I also propose to provide a printing plate 45 wherein the frictional, resilient printing or impression-producing face may have delicate or thin printing characters formed thereon and which plate may be used under 50 conditions and with results similar to offset press work for thin, light-weight paper of any surface finish.

Furthermore with my plate I am able to 55 produce relief printing resembling full tone, half tone, or a combination of these,

or such work as is attained in photography and rotogravure printing. I accomplish this by varying the pressure on the plate during the printing operation, thereby enabling me to spread the resulting dotted 60 surface, or by varying the resiliency of the plate itself, as conditions may warrant.

With the above recited objects and others of a similar nature in view, my invention consists in the construction, combination 65 and arrangement of parts set forth in and falling within the scope of the appended claims.

In the drawings,

Figure 1 is a cross sectional view of a 70 plate embodying my invention.

Fig. 2 is a view showing conventionally a press and a matrix sheet for the plate.

Fig. 3 is a cross sectional view taken 75 through a casting box showing the plate being made with the matrix.

One manner of practising my invention to produce a plate such as herein described is as follows: The first step to be taken is the formation of a matrix or mold from 80 which the plate is cast and to accomplish this a body of type conventionally illustrated at 1 is locked in the ordinary chase and placed upon the bed of a suitable press, conventionally illustrated at 2. I then impose on the face of this body of type a 85 matrix-forming sheet 3 which is preferably of composite form, that is to say, comprises a facing sheet of lead and a backing sheet of a phenolic condensation product such as 90 "bakelite" or "condensite," or the like. Such a composite sheet is shown and described in my copending application Ser. No. 98,909, filed May 20, 1916. The lead facing sheet of this composite sheet is placed in contact 95 with the type faces and the press is operated to embed such type faces in the composite sheet, thus forming indentations or depressions which are complementary to or correspond with the type faces.

The matrix thus formed is now removed from the press and the lead face thereof may, if necessary, be chemically cleaned with any suitable chemical. The matrix is then transferred to a casting box, conventionally shown 105 at 4 with the lead or molding face of such matrix being uppermost. On this uppermost face of the matrix is imposed a layer or sheet of vulcanizable gum rubber 5, of any suitable thickness, say for instance of from 110

3 to 10/1000 of an inch in thickness. On top of this rubber layer or sheet I now impose a sheet 6 composed of a phenolic-condensation product, such as "condensite" or "bake-lite," a film or coating of binding material such as a mixture of rubber cement and wood flour being spread upon either of the contacting faces of the rubber sheet and the phenolic sheet in order to insure permanent cohesion or union of these two sheets when the plate is finished. Heat and pressure are now applied for a sufficient length of time to soften the phenolic condensation material, to vulcanize the rubber to the desired degree of resiliency and to intimately unite the two sheets through the rubber cement binder. At the same time of course the heat and pressure applied to the elements assembled in the casting box as mentioned will result in producing in the rubber sheet, printing and non-printing portions, which are complementary to the similar portions formed in the molding face of the matrix. Of course these type printing and non-type printing portions in the rubber sheet or layer are reproduced during the application of the heat and pressure, in the phenolic backing sheet. After the assembled elements have been subjected to the above mentioned action in the casting box for a sufficient length of time the matrix with the now formed printing plate is removed from the casting box and the rubber impression producing face sheet with its phenolic or cementitious backing is stripped from the matrix and is ready for use. If desired, the rubber printing or impression producing face sheets may be first made in the matrix, and the backing sheets subsequently united with the face sheets instead of simultaneously applying each cementitious backing sheet to the rubber face sheet at the time of forming the latter.

While I have herein shown and described one particular embodiment of my invention, I wish it to be understood that I do not confine myself to all the precise details herein set forth by way of illustration as modification and variation may be made without departing from the spirit of the invention or exceeding the scope of the appended claims.

What I claim is:

1. A printing plate comprising a rubber facing sheet having hollow type elevations and a backing sheet composed of a layer of relatively hard synthetic resin supporting said facing sheet having portions filling the hollows of the type elevations. 55

2. A printing plate comprising a rubber facing sheet having printing characters on one face thereof to constitute the printing face and a backing sheet of relatively hard and rigid phenolic condensation product united with and supporting said facing sheet. 60

3. The herein described method of making 65 a printing plate which comprises imposing a sheet of moldable material upon a sheet of resilient material, placing the two sheets upon a suitable matrix with the resilient sheet in contact with the matrix, and then 70 subjecting the two sheets while on the matrix to heat and pressure to mold in the resilient sheet characters complementary to those of the molding face of the matrix and to cause the material of the moldable sheet to fill the hollows formed in the back of the resilient sheet. 75

4. The herein described method of producing a printing plate which consists in 80 subjecting a sheet of resilient material and a sheet of plastic material to the action of heat and pressure against a matrix to produce in the resilient sheet characters complementary to those of the mold face of the 85 matrix and to cause the material of the moldable sheet to fill the hollows formed in the back of the resilient sheet, and to harden and set the plastic material.

5. The herein described method of making 90 a printing plate which comprises placing a sheet of vulcanizable rubber against the molding face of a matrix, uniting a sheet of phenolic condensation product to the back of the facing sheet by means of a suitable binder and applying heat and pressure to 95 unite the two sheets and to reproduce printing characters in the rubber sheet which are complementary to those of the matrix.

Signed at New York, in the county of New York, and State of Illinois, this 25th 100 day of November, A. D. 1916.

EMIL E. NOVOTNY.
